UNITED STATES PATENT OFFICE.

JOSEPHINE VORNHULZ, OF WASHINGTON, DISTRICT OF COLUMBIA.

CARPET-FASTENER.

1,315,060.

Specification of Letters Patent. Patented Sept. 2, 1919.

Application filed February 17, 1919. Serial No. 277,584.

To all whom it may concern:

Be it known that I, JOSEPHINE VORNHULZ, a citizen of the United States, residing at Washington, District of Columbia, have invented certain new and useful Improvements in Carpet-Fasteners, of which the following is a specification.

This invention relates to separable fasteners and more particularly to carpet fasteners. 10 The object of the invention is to provide a combined stiffener and fastener for the edges of carpets, rugs, and the like.

Another object is to provide a simple, cheap and efficient device of this character, 15 one member of which is permanently secured to the carpet and the other to the floor, said members being equipped with means for interlocking engagement.

With the foregoing and other objects in 20 view, which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

In the accompanying drawings:—

30 Figure 1 represents a bottom plan view of a piece of carpet having one member of this improved fastener secured thereto ready for use,

Fig. 2 is an enlarged detail transverse section showing the carpet secured by said fastener to the floor,

Fig. 3 is a detail perspective view of the floor carried member of the fastener, and

Fig. 4 is a similar view of the carpet carried member.

In the embodiment illustrated, the carpet C is shown having secured to its lower face adjacent one edge thereof, a plurality of fasteners arranged in longitudinal alinement 45 and each comprises a bar or strip 1 having alternately arranged tongues 2 and loops 3 extending laterally from one edge and lying in the same plane with the bar. These tongues, loops and the bar are preferably struck from a single sheet of metal, preferably of aluminum. The loops 3 are here shown rectangular in form and while any desired number may be employed, three are shown carried by each bar 1 with two 50 tongues 2 arranged between them. The bar 1 has a plurality of longitudinally spaced

thread receiving apertures 4 therein, disposed preferably at the base of each tongue, three being here shown, and each tongue is equipped with similar apertures 5. These 60 bars are designed to be placed adjacent the edge of the carpet C on its lower face as shown in Fig. 1, with the loops and tongues extending toward the edge thereof, and they are secured to the carpet by threads 6 which 65 are passed through the apertures 4 and 5 in the bar and tongues.

Coöperating fastening elements 7 are designed to be driven into the floor F and one is used for each loop 3. Each of these members 7 comprises a plate 8 having an in-turned hook-like lip 9 at one end and a tapered penetrating prong 10 extending at right angles from its lower face midway its ends. These prongs 10 are designed to be 70 driven into the floor F as is shown clearly in Fig. 2, with the hook shaped lip turned inwardly and said hook positioned outwardly as shown in Fig. 2.

In the use of this fastener, the members 7 80 are driven into the floor F at distances corresponding to the distance between the loops 3 carried on the lower face of the carpet C and after being so driven these loops 3 are engaged with the members 7 by passing the 85 loop 3 over the front end of the fastener 7, moving said loop rearward until hook 9 is passed through and up over the loop, then moving loop 3 back to cause the front end of the loop to engage prong 10 as shown in 90 Fig. 2 and thereby detachably but releasably connect the carpet to the floor. Should the carpet creep forward as it frequently does, the front edge of the front bar of loop 3 will engage hook 9 and limit its movement. 95

When it is desired to remove the carpet or rug for cleaning, storage, or other purposes, the carpet edge is lifted and the loops are moved forwardly and downwardly out of engagement with the prongs 10 and the ends 100 11 passed down through the loops and said loops moved forward to disengage them from the member 7. The members 7 may then be withdrawn from the floor by a tack puller or any other suitable implement and 105 stored away for future use, the fasteners carried by the carpet being allowed to remain.

From the foregoing description taken in connection with the accompanying drawings, the advantages of the construction and of 110 the method of operation will be readily apparent to those skilled in the art to which

the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention, 10 what I claim as new and desire to secure by Letters Patent, is:—

1. A fastener of the class described comprising two coöperating separable members, one being in the form of a bar having a loop 15 extending laterally from one edge and in the same plane with the bar and equipped with attaching means, and the other in the form of a metal plate with a securing prong extending at an angle from one face, and an 20 inturned hook-like lip spaced from said prong.

2. A fastener of the class described comprising two coöperating separable members, one being in the form of a bar having a loop 25 and a tongue extending laterally from one edge and in the same plane with the bar and spaced from each other, said tongue and bar having apertures for a securing thread, the other member being in the form of a metal 30 plate with a securing prong extending at right angles from one face and an inturned hook-like lip spaced from said prong and arranged on the same face therewith.

3. A fastener of the class described comprising two coöperating separable members, 35 one in the form of a bar having a plurality of alternating longitudinally spaced tongues and loops extending laterally from one edge and in the same plane with the bar, said bar and tongues having thread receiving apertures therein, the other members being each in the form of a metal plate having a securing prong extending at right angles from one face midway its ends and an inturned hook-like lip on one end and on the same 40 face as said prong.

4. A fastener of the class described comprising coöperating separable members, one in the form of a bar having a plurality of 45 alternating, longitudinally spaced tongues, and loops extending laterally from one edge and in the same plane with the bar, the loops being rectangular in form, said bar and tongues having thread receiving apertures therein, the other members being each 50 in the form of a rectangular spring metal plate having a securing prong extending at right angles from one face midway its ends, and an inturned hook-like lip on one end and on the same face as said prong.

In testimony whereof I affix my signature in presence of two witnesses.

JOSEPHINE VORNHULZ.
